United States Patent Office

Des. 186,418

Patented Oct. 20, 1959

186,418

AIRPLANE

Edward F. Burton, Los Angeles, Calif., assignor to Douglas Aircraft Company, Inc., Santa Monica, Calif.

Application January 4, 1957, Serial No. 44,401

Term of patent 7 years

(Cl. D71—1)

Fig. 1

Fig. 2

FIG. 3.

FIG. 4.

Figure 1 is a top plan view of an airplane embodying my novel design;

Figure 2 is a side elevation of the same;

Figure 3 is a perspective view taken forward from the top and one side of the airplane; and

Figure 4 is a front elevation of the same.

I claim:

The ornamental design for an airplane, substantially as shown.
